UNITED STATES PATENT OFFICE.

EMERSON P. JENNINGS, JR., OF LEHIGHTON, PENNSYLVANIA.

PLATEN-GRIPPER.

1,253,248.

Specification of Letters Patent. Patented Jan. 15, 1918.

Original application filed March 30, 1916, Serial No. 37,725. Divided and this application filed October 9, 1916. Serial No. 124,494.

To all whom it may concern:

Be it known that I, EMERSON P. JENNINGS, Jr., a citizen of the United States, residing at Lehighton, in the county of Carbon and State of Pennsylvania, have invented certain new and useful Improvements in Platen-Grippers, of which the following is a specification, reference being had therein to the accompanying drawings.

10 This invention relates to platen grippers for printing presses and the present application is a division of the application filed by me March 30th, 1916, Ser. No. 87725.

The object of the invention is to provide 15 platen, or impression, grippers which will be of a very simple and inexpensive construction and which will be positively operated in timed relation to the movements of the press.

20 A further object of the invention is to provide platen grippers in combination with sheet feeding mechanism and to so construct and arrange the same that they will in no way interfere with the operation of the feeding mechanism but will operate in timed relation to the movements thereof.

Other objects of the invention will appear as the mechanism is described in detail.

In the accompanying drawings, Figure 30 1 is a side elevation, partly broken away, of a printing press embodying my invention; Fig. 2 is a perspective view of the platen of such a press showing the platen grippers in detail; Fig. 3 is a side elevation of the sheet 35 feeding devices showing the platen grippers in operative relation to the platen; and Fig. 4 is a similar view showing the platen grippers spaced away from the platen.

In these drawings I have illustrated one 40 embodiment of the invention and have shown the same as applied to a bed and platen press in which the form bed moves in a horizontal right line toward and away from the platen and which is provided with an automatic sheet feed, but it will be understood that this press is chosen for the purpose of illustration only and that the invention is applicable to presses of various kinds, either with or without feeding mechanism.

As shown in the drawings the press as a whole comprises a main frame 1 consisting of side members spaced apart and tied together by tie rods and connecting devices 55 and serving to support the various parts of

the printing and feeding mechanism. A normally stationary platen 2 is mounted near one end of the press and a form bed 3 is mounted for movement toward and from the platen. In the type of press here shown the 60 form bed has combined therewith an inking drum 4. The combined form bed and inking drum is provided at its ends with trunnions mounted in guide blocks 5 which are slidably mounted in guideways 6 formed in 65 the side walls of the main frame 1. These trunnions are connected by pitmen 7 with crank wheels which are here shown as gears meshing with pinions 9 mounted on a shaft 10 to which power may be applied in any 70 suitable manner.

Mounted on the main frame of the press above the platen is a sheet supporting and separating device comprising a support for a pile of sheets of paper or the like and 75 having a separating member comprising a series of suction blocks 15 to engage and separate one sheet from the pile of sheets. In the present arrangement the separating member engages the lowermost sheet and 80 turns the forward edge of the same downward into a position to be gripped by conveying grippers, 50 and 51, which draw the sheet from beneath the pile and move the same into printing position on the platen. 85 The conveying grippers are mounted on a shaft 48 carried by brackets 49 which are rigidly secured to vertically movable rack bars 37 arranged on the respective sides of the platen and having at their upper ends 90 cam bars 36 which are provided with cam grooves 35 to engage a stud or roller 34 and actuate the sheet separating member 15. The rack bars 37 mesh with gears 38 mounted on a shaft 39 extending transversely of 95 the main frame and having secured thereto a pinion 40 which meshes with a horizontal rack bar 20 which in turn is secured to one of the slide blocks 5, thus causing the rack bars and cam bars to reciprocate in timed 100 relation with the movements of the form. The opening and closing of the conveying grippers, 50 and 51, is brought about by trip devices or cams near the face of the platen and so arranged that as the grippers travel 105 up or down they will be opened or closed at the proper time for the performance of their functions. The details of construction and operation of the sheet separating device and the conveying grippers are not neces- 110

sary to an understanding of the present invention and a full description of the same will be found in the above mentioned application.

- 5 The platen or impression grippers comprise strips of metal or fingers 80 having at their upper ends bearings 79 by means of which they are adjustably mounted upon the supporting rod 81 which extends transversely to the platen near the upper edge thereof. The supporting rod 81 is so mounted that the fingers 80 may be moved toward and from the face of the platen and the fingers are so mounted on the rod that they 10 will engage the sheet near the lateral edges thereof, thus, when moved into their operative positions, pressing the sheet firmly against the face of the platen and retaining the sheet in that position during the taking 15 of the impression. Preferably the fingers and their supporting rod move bodily lengthwise of the press and to so support the rod I have mounted the ends thereof, respectively, in slide bars 82 arranged for longitudinal sliding movement near the opposite sides of the platen, and preferably mounted in bearing brackets 82^a rigidly secured to and projecting above the top of the casting or body structure of the platen. In order 20 that the gripping fingers may be operated in timed relation with the movements of the conveying grippers I have provided means for actuating the same from the same part or parts which control the movement of the 25 conveying grippers. To this end I have provided one, or if desired both, of the slide bars 82 with pins or rollers 83 arranged to be engaged by a cam bar 85 rigidly secured to the adjacent bar 36 and having a cam slot 30 84 opening through the lower edge thereof to receive the pin 83. Hence on the downward movement of the bars 36 and the conveying grippers the cam bar 85 will actuate the slide bars 82 and move the gripping 35 fingers 80 toward the platen, this movement being so timed that the gripping fingers will engage the sheet on the platen immediately following its movement into printing position. The cam slot 84 has a vertical 40 portion which serves to hold the gripping fingers in their operative positions during the further movement of the conveying grippers. Obviously, upon the return movement of the bars 36 and the conveying grippers the cam bar 85 will act upon the pin 83 to move the gripping fingers out of engagement with the sheet on the platen, thus releasing the same and permitting it to be 45 removed.
- 50 The operation of the mechanism will be clearly understood in connection with the description of the mechanism thereof and it will be apparent that both the platen gripper mechanism and its operating devices are 55 very simple in construction and operation

and that it is of a strong durable character and is not liable to become disarranged in the normal operation of the press. Further, it will be apparent that the platen grippers are so connected with the conveying grippers as to operate in timed relation thereto, thus permitting the gripping devices to be moved out of the way of each other in the normal operation of the feeding mechanism.

While I have shown and described one embodiment of my invention it will be understood that the same has been chosen for the purposes of illustration only, and that I do not desire to be limited to the details of construction shown and described, for obvious modifications will occur to a person skilled in the art.

Having thus fully described my invention, what I claim as new and desire to secure by Letters Patent, is:

1. In a printing press, a printing couple, one member of which is movable toward and from the other member, platen grippers mounted for movement into and out of operative position with relation to the last-mentioned member, and means actuated from said movable member to positively move said grippers into and out of their operative positions. 90
2. In a printing press, a printing couple, one member of which is movable toward and from the other member thereof, platen grippers comprising a supporting structure slidably mounted near one edge of the last-mentioned member, fingers carried by said supporting structure, and means for imparting sliding movement to said supporting structure to move said fingers toward and from said last-mentioned member in timed relation to the movement of said movable member. 95
3. In a printing press, a printing couple, one member of which is movable toward and from the other member thereof, bars slidably mounted near one edge of the last-mentioned member, fingers carried by said bars, and means for actuating said bars to move said fingers toward and from the face of said last-mentioned member. 100
4. In a printing press, a printing couple, one member of which is movable toward and from the other member thereof, bars slidably mounted near the top of said last-mentioned member, fingers depending from said bars, and an operative connection between said bars and said movable member to move said fingers toward and from said last-mentioned member. 110
5. In a printing press, a printing couple, one member of which is movable toward and from the other member thereof, bars slidably mounted near one edge of the last-mentioned member, a supporting rod carried by said bars, fingers secured to said rod, and means for actuating said bars to move said 120
- 130

fingers toward and from said last-mentioned member in timed relation to the movements of said movable member.

6. In a printing press, a printing couple, one member of which is movable toward and from the other member thereof, bars slidably mounted on the top of the last-mentioned member, a support carried by said bars, fingers secured to said support, and means for actuating said bars to move said fingers toward and from said last-mentioned member.

7. In a printing press, a printing couple, one member of which is movable toward and from the other member thereof, bars slidably mounted near one edge of the last-mentioned member and connected one with the other, fingers carried by said bars, a cam extending transversely to said bars, one of said bars having a part to coöperate with said cam, and means to actuate said cam.

8. In a printing press, a printing couple, one member of which is movable toward and from the other member thereof, bars mounted for sliding movement along the upper edge of the last-mentioned member and con-

nected one to the other, fingers carried by said bars for movement toward and from the face of said last-mentioned member, vertical reciprocating cam bars arranged on the opposite sides of said last-mentioned member, said bars having parts to coöperate with the cams, and means to impart reciprocatory movement to said cam bars.

9. In a printing press, a printing couple, one member of which is movable toward and from the other member thereof, bars mounted for sliding movement along the upper edge of the last-mentioned member and connected one to the other, fingers carried by said bars for movement toward and from the face of said last-mentioned member, vertically reciprocating cam bars arranged on the opposite sides of said last-mentioned member, said slidable bars having parts to coöperate with the cams, and an operative connection between said cam bars and the movable member of said printing couple.

In testimony whereof I affix my signature hereto.

EMERSON P. JENNINGS, JR.
